UNITED STATES PATENT OFFICE.

CHARLES O. BLACKWELL, OF HANNA, WEST VIRGINIA, ASSIGNOR OF ONE-HALF TO
JOHN B. YEAGER, OF WALKER, WEST VIRGINIA.

CELLULAR PACKING STRUCTURE.

1,167,620.

Specification of Letters Patent. Patented Jan. 11, 1916.

Application filed June 19, 1915. Serial No. 35,162.

To all whom it may concern:

Be it known that I, CHARLES O. BLACKWELL, a citizen of the United States, residing at Hanna, in the county of Wood and State 5 of West Virginia, have invented certain new and useful Improvements in Cellular Packing Structures, of which the following is a specification, reference being had to the accompanying drawings.

10 My invention relates to egg cells or cases, and particularly that variety of egg cell or case which is composed of intersecting strips of pasteboard or like material, the strips being notched or slotted so as to have locked 15 engagement with each other.

The general object of my invention is to provide an egg case of the above character which will be more durable and stronger than egg cases as ordinarily constructed and 20 in which the strips will be more securely interlocked with each other so as to prevent the accidental detachment of the several strips.

A further object of my invention is to so 25 form the case that it may be readily assembled and may be cheaply made.

Other objects will appear in the course of 30 the following description.

My invention is illustrated in the accompanying drawings, wherein:

Figure 1 is a perspective view of my cell structure in assembled position; Fig. 2 is a face view of one of the strips; Fig. 3 is a face view of the other strip.

35 Referring to these figures, it will be seen that my improved egg case is composed of a series of parallel strips or slats 2 and a series of parallel strips or slats 3 normally intersecting the strips 2 at right angles. The 40 strips 2 are formed with a plurality of pairs of notches or slits 4 extending inward from both side edges, the notches of each pair being in alinement. Each strip 3 has the longitudinally extending end slots 5 and the 45 intermediate slot 6. The end slots 5 are each intersected by two slots 7 and 7^a at right angles to the end slot. The slot 7^a is disposed inward of the extremity of the slot 5, as shown clearly in Fig. 2. The adjacent 50 walls of the slots 7 and 7^a at the intersection of these slots with the slot 5 are cut away as at 8. The intermediate slot 6 is spaced in-

tervals is intersected by slots 7 and 7^a at right angles to the slot 6, the end slots 7^a, however, being disposed inward of the ends 55 of the slots 6. As illustrated there are three slots 7 intersecting the slot 6. The inner walls of the end slots 7 are cut away, as at 8, and the wall of the middle slot 7 is also cut away as at 8. The purpose of cutting 60 away the wall of the slots 7 and 7^a as at 8 is to permit the strips 2 to be rotated within the slots 7 to bring these strips 2 into alinement with the slots 5 and 6 and thus permit the withdrawal of the strips 2 from the interlocked engagement with the strips 3. It 65 will be seen that with this construction, when it is desired to assemble the strips 2 and 3, the strips 2 are threaded through the slots 5 and 6 of the strip 3 and then turned so as to 70 dispose the necks between the notches 4 of the strips 3 within the slots 7 and 7^a. The necks 4^a between the notches 4 of the strips 2 are slightly wider than the entrance into the slots 5 and 6 formed by the cut away 75 portions 8, and as a consequence when the strips 2 are in place within the slots 7 and 7^a the strips 2 will be held interlocked with the strips 3 and at right angles thereto, thus forming a cellular structure which may be 80 folded flat for transportation but which may be readily opened up for insertion in an egg crate to thereby form a series of egg compartments or cells. Because of the fact that the strips are interlocked with each other in 85 the manner above described, they cannot readily become detached, the cellular structure formed by the slats will be more substantial than with the ordinary construction, and may be used a large number of times 90 without damage.

Having thus described my invention, what I claim is:

A cellular structure comprising two sets of intersecting strips, one set being provided 95 with a plurality of uniformly spaced slits extending inward from its side edges, the other set being formed with a plurality of longitudinally extending slots having a length equal to the width of the first-named 100 strips and intersected by transversely extending slots having a length equal to the space between the inner ends of each pair of slits on the first named set of strips, the wall

of each intersecting slot being cut away at the intersection of the slots whereby to permit the first-named set of strips to be inserted within the longitudinally extending slots and then rotated out of alinement with the longitudinal slots and into position within the intersecting slots.

Copies of this patent may be obtained for five cents each, by addressing the "Commissioner of Patents. Washington, D. C."

In testimony whereof I hereunto affix my signature in the presence of two witnesses.

CHARLES O. BLACKWELL.
